JOURNAL BOX STRUCTURE

Theodore R. Weber, Latrobe, Pa., assignor to
American Locomotive Company, New York,
N. Y., a corporation of New York

Application October 4, 1944, Serial No. 557,166

1 Claim. (Cl. 308—47)

1
This invention relates to journal box structures. More particularly, this invention relates to journal box structures of the general type shown in U. S. patent to A. N. Lukens, No. 1,930,650, wherein an eyeless lid is retained in spring-pressed engagement on a journal box by a torsion spring having spaced legs and by a hood housing the spring. The present invention is an improvement of the structure of the Lukens patent.

An object of the present invention is to provide an improved journal box structure of the aforementioned type having a truly universal connection between the lid and hood as well as between the spring legs and lid.

A further object is to provide an improved journal box structure hood.

Other and further objects of this invention will appear from the following description, the accompanying drawings and the appended claim.

Referring to the drawings forming a part of this application, Figure 1 is a front view of a journal box structure embodying the present invention; Fig. 2 is a section on the line II—II of Fig. 1, parts being shown in full, the journal box being indicated in dash lines; Fig. 3 is a section on the line III—III of Fig. 4, parts being shown in full; Fig. 4 is a fragmentary side view of the journal box structure partly shown in section; Fig. 5 is a section on the line V—V of Fig. 2, parts being shown in full; Fig. 6 is a view similar to Fig. 1 of a modified structure embodying the present invention; Fig. 7 is a section on the line VII—VII of Fig. 6, parts being shown in full, the journal box being indicated in dash lines; Fig. 8 is a section on the line VIII—VIII of Fig. 7, parts being omitted; Fig. 9 is a section on the line IX—IX of Fig. 7, parts being shown in full; Fig. 10 is a fragmentary view taken similar to Fig. 9, showing a modified ball and socket connection between the lid and hood; Fig. 11 is a fragmentary vertical sectional view of another modified structure embodying the present invention; and Fig. 12 is a fragmentary horizontal sectional view taken similarly to Fig. 5 of a further modified structure embodying the present invention.

The journal box structure shown in Figs. 1 to 5 includes an open face journal box 1 having an orificed hinge cam lug 2 at its top. The open face of the box is closed by an eyeless lid 3 having an outwardly curved portion located centrally of the open face and curved in a plane parallel to the vertical center plane of the open face providing two curved spring seats 4 on its outer face and spaced equally from the aforesaid center plane. The curved portion is provided with a flat seat 5 on its outer face centrally disposed of the open face.

A hood 6 is connected to the box by a pin 7 disposed in the orifice of the lug 2. Pin 7 has

2
a shoulder 8 cut into each of its ends. Hood 6 is made of pressed steel. It has half bearing eyes 9 open at the front and engaging the pin 7 at the rear. The side walls of the hood adjacent the eyes are provided with elongated holes 10 through which the pin passes, the rear face of said hole 10 being in alignment with and forming an extension of the adjacent half bearing eye 9. A retainer 11 is formed on each eye 9 by shear-cutting the eye to form a slit 12 and then pressing the portion outwardly of the cut forwardly to form a shoulder 13, shoulders 13 coating with shoulders 8 to retain the pin against displacement and to prevent it from rotating in the hood and in the lug 2 when the open face of the box is closed by the lid. An entirely cylindrical pin may be employed if desired of substantially the same length as the distance between the retainer shoulders 13. The shoulders 13 will retain this pin but will not prevent it rotating.

The elongations of the holes 10 provide clearance in front of the pin so that the shoulders 8 and 13 can be moved out of alignment for removal or insertion of the pin from or into the orifice of the lug. The end portions of the pin are visible, as is clearly shown in Fig. 1, at the front providing the advantage that the pin can be inspected to determine that it is of the right diameter and length, thus eliminating the danger of an undersize pin being employed which would cause misalignment and excessive play.

The hood has a spherical socket 14 in its outer face opposite the seat 5. A ball member 15 is disposed in this socket and rigidly connected to the lid by a bolt 16, the ball member having an orifice through which the bolt passes and the socket having an orifice in which is loosely disposed a spacer 17 engaging the seat 5, the spacer having an orifice through which the bolt 16 passes. The spacer is held immovably against the ball member 15 and the seat 5 by the bolt 16. The hood further has two spaced curved seats 18 above the socket 14.

A torsion spring 19 is disposed between the lid and hood. It has two spaced straight cylindrical legs 20 pressing with point contact on the forward part of the seats 4, two coils 21 disposed in the seats 18 and a yoke 22 engaging, through a roller 23, the cam of lug 2. The spring-pressed point contact of the yieldable legs with the seats 4, the curvature of the seats 4 and the ball and socket connection provide a truly universal connection between the lid and hood permitting the lid to seat firmly against the box. The legs 20 engage the seats 4 midway between the top and bottom of the open face of the box so that the spring pressure is exerted centrally of the open face and the lid is pressed evenly at all sides against the box. The spring is proportioned so that it exerts substantially the same pressure on

the lid and lug. The upper edge of the lid is in close proximity with the hood shoulders 24 preventing the lid turning about the bolt 16 when not in engagement with the box.

The structure shown in Figs. 6 to 9 differs from the structure of Fig. 1 mainly in that the spring legs 20' terminate in curved portions 25 disposed in curved recesses 26 formed in the lid, the recesses being situated similarly to the seats 4 and performing the same functions. While the hood and hinge pin differ from the hood and hinge pin of Fig. 1, either of the hoods and its hinge pin may be used with either of the lids and its spring if desired. A rivet 16' is shown instead of the bolt 16 but the bolt may be employed if desired.

A ball and socket connection is shown in Fig. 10 which may be employed in either of the structures of Fig. 1 or Fig. 6. It eliminates the bolt and rivet, which may become loose from service, and substitutes therefor a pressed steel member having a ball part 15" and a stem part 16" welded in a hole 27 in the lid.

The structure shown in Fig. 11 differs from the structure of Figs. 6 to 9 in that the recesses 26 are eliminated, the curved ends 25''' of the spring legs engaging a flat portion of the lid.

The structure shown in Fig. 12 differs from the structure of Figs. 1 to 5 in that the socket 14''' is formed in the lid 3''' and the rivet 16''' is secured to a flat portion of the hood 6'''.

The curved portions 25 in their recesses 26 (Figs. 6 to 10) prevent the lid from turning about the axis of the universal joint when the lid is not in engagement with the box.

The hoods of the various embodiments (Figs. 1, 6, 10, 11 and 12) have, respectively, side walls 28, 28', 28'', 28''' and 28'''' which have their rear edges in close proximity to the lid. In the case of the embodiment of Figs. 1 to 5 a portion of each of the side walls 28 is in close proximity to the outer side of the adjacent seat 4, this providing another means for preventing the lid 3 from turning about the axis of the bolt 16 of the universal joint when the lid is not in engagement with the box.

When the lid of each of the various embodiments is swung open it maintains engagement at its upper edge with the box until it engages the lower edge of the hood. The hood and lid are then swung bodily. Conversely, when the lid is swung closed, its upper portion first engages the hood side wall rear edges and then the lid and hood are swung bodily.

Other parts of the structures of Fig. 6, Fig. 10, Fig. 11 and Fig. 12 corresponding to like parts of the structure of Fig. 1 are designated by like reference numerals, with, respectively, one, two, three or four accents added.

The side walls 28 of the embodiment of Fig. 1 are provided with aligned holes 29, and the side walls of the hoods of the other embodiments are similarly provided with these holes. These holes are for use in attaching and detaching the hinge pin to and from the box. To this end a bar is passed through the holes behind the legs of the yoke 22 of the spring, the spring being tightened slightly to permit this, which is accomplished according to usual practice.

Types of pin retainers other than that shown in Figs. 1 to 4 and involving the same principle are contemplated within the scope of the present

invention. For instance the end of the eye may be merely bent at a right angle over the rear of the pin end or over the pin shoulder as the case may be, or may be offset as shown in Figs. 1 to 4 but without forming the slit. Furthermore such types of retainers may be employed at only one end of the pin, permitting the pin to be withdrawn through this side of the hood. In such instances the end of the pin at the opposite side of the hood may be straight or shouldered as required, and at this opposite side the orifice in the hood need not be elongated and any suitable retainer may be used at this opposite side. As an example, a suitable retainer at this opposite side would be provided by permanently bending an extended portion of the adjacent eye so that it will be disposed over the end of the pin. The pin would be withdrawn through the elongated orifice side of the hood, and to accomplish this the hood at this side would be manipulated so that the retainer at this side would clear the pin in the manner previously stated.

While there have been hereinbefore described approved embodiments of this invention it will be understood that many and various changes and modifications in form, arrangement of parts and details of construction may be made thereto without departing from the spirit of the invention and that all such changes and modifications as fall within the scope of the appended claim are contemplated as a part of this invention.

The invention claimed and desired to be secured by Letters Patent is:

A closure for an open-faced journal box having a cam hinge lug adjacent the upper margin thereof, comprising a hood having a centrally apertured spherical recess struck inwardly out of the plane thereof; a centrally apertured spherical washer movably disposed in said recess; a pintle hinging said hood to said lug; an eyeless closure lid closing the open face of said journal box and having an aperture at the center of said open face and an arcuate ridge struck outwardly out of the plane of said lid at opposite sides of said aperture, said apertures in said lid, recess and washer being in alignment; means extending through said apertures connecting said lid to said spherical washer for limited universal movement of said lid relative to said hood and journal box; and a torsion spring operatively disposed between said hood and lid, presenting two spaced legs of circular cross section having point contact on said arcuate ridges with the axes of said legs perpendicular to the axis of said ridges, said legs terminating in two spaced coils in contact with said hood and said coils terminating in a loop engaging said cam lug whereby said spring exerts pressure on said hood and lid in all positions of movement relative to said journal box.
